UNITED STATES PATENT OFFICE.

AUGUST S. HELD, OF FREEPORT, ILLINOIS, ASSIGNOR TO STOVER MANUFACTURING COMPANY, OF FREEPORT, ILLINOIS, A CORPORATION OF ILLINOIS.

MOP-HEAD.

SPECIFICATION forming part of Letters Patent No. 699,312, dated May 6, 1902.

Application filed October 30, 1901. Serial No. 80,570. (No model.)

To all whom it may concern:

Be it known that I, AUGUST S. HELD, a citizen of the United States of America, residing at Freeport, in the county of Stephenson and State of Illinois, have invented certain new and useful Improvements in Mop-Heads, of which the following is a specification.

This invention has for its object the production of improved heads for holding mops; and it consists of certain new and useful features of construction and combinations of parts hereinafter fully described, and specifically pointed out in the claims.

Referring to the accompanying drawings, which form a part of this specification, Figure 1 is a top plan view of a mop-head embodying my invention. Fig. 2 is a section of the same at the dotted line 2 2 in Fig. 1. Fig. 3 is a side view of the mop-head with the jaws thereof in position to admit a mop between the same. Figs. 4 and 5 are end views of a ring which serves as a connecting means between the ends of a wire forming the movable jaw of the mop-head. Fig. 6 is a section at the dotted line 6 6 in Fig. 5 of parts there shown.

Like letters of reference indicate corresponding parts throughout the several views.

A is a mop-stick.

B B' represent a casting composing the fixed clamping-jaw of the mop-head and its handle-socket.

C is a counterpart movable clamping-jaw parallel with the fixed jaw B, having its ends C' C² extending and converging rearwardly and united by means of a collar D, which has a central opening D' therein indented with notches D² in the perimeter thereof, and is provided with trunnions D³, about which the ends C' C² of the jaw C are bent, as shown in Figs. 1 and 3.

E is a lever fulcrumed by one end E' through the hook-stud E² and pivot-bearing E³ to the handle A and extending therefrom rearwardly through the collar D. A convenient means of connecting the lever E with the collar D is to have lugs E⁴ so formed thereon that they will pass through the notches D² in the perimeter of the opening therein, as

clearly shown in Fig. 4. Such lever may then 50 be turned to the position shown in Fig. 5. The lugs E⁴ thereon will then retain the lever E and its encircling collar in permanent engagement.

F is a spring interposed between the collar D and a bearing, as F', at the lower end portion of the lever E.

Fig. 3 shows the lever E raised, which operation carried the movable jaw C away from the fixed jaw B, so as to allow the mop G to 60 be introduced between them. The lever E is next lowered to the position shown in Figs. 1 and 2 against the action of the spring F, which holds the jaw C tightly against the intervening mop G and stationary jaw B. 65

Having thus described my invention, what I claim as new, and desire to secure by Letters Patent, is—

1. In a mop-head, in combination, a handle, a casting comprising a fixed clamping-jaw and 70 a handle-socket, a counterpart movable clamping-jaw—parallel with the fixed jaw—having its ends extending and converging rearwardly and united by connecting means, a lever fulcrumed, by one end, to the handle, and extending therefrom rearwardly through the connecting means of the clamping-jaw ends, and a spring interposed between such connecting means and a bearing at the lower end portion of the lever, substantially as and for 80 the purpose specified.

2. The combination of a handle A, with a fixed clamping-jaw B fast thereto, a movable clamping-jaw C having its ends C' C² extending and converging rearwardly, means, as a 85 collar D, for uniting the ends C' C² of the jaw C, a lever E fulcrumed, by one end, to the handle A, and extending therefrom through the collar D, and a spring F normally acting to clamp the jaw C against the jaw B, substantially as and for the purpose specified.

In testimony whereof I have signed my name to this specification in the presence of two subscribing witnesses.

AUGUST S. HELD.
